UNITED STATES PATENT OFFICE.

JOSEPH T. BARTON AND EDWARD J. O'LEARY, OF CHICAGO, ILLINOIS.

PRINTER'S TYPE PLANER.

Application filed March 23, 1921. Serial No. 454,977.

To all whom it may concern:

Be it known that we, JOSEPH T. BARTON and EDWARD J. O'LEARY, both citizens of the United States, residents of Chicago, in 5 the county of Cook and State of Illinois, have invented certain new and useful Improvements in Printers' Type Planers, of which the following is a specification.

This invention relates to improvements in 10 printers' type planers. The device at present employed in printing shops for planing type forms usually consists of a rectangular block of wood which is laid on the type form, and a mallet with which the block is 15 tapped as the latter is moved over the face of the type form.

The chief objection to this old and common form of type planer lies in the fact that there is no uniformity in the blow or 20 pressure applied to the block by the use of the mallet, and the face of the type is frequently marred and otherwise injured, so that the form, when printed, instead of being sharp and distinct, is frequently more 25 or less blurred.

Again, the mallet being separate from the block is sometimes lost or mislaid and valuable time is wasted in trying to locate it. Furthermore, the constant pounding of the 30 mallet creates an objectionable noise, and occasionally involves injury to the hands or fingers of the operators when planing type.

Among the leading objects of our present invention, are, to provide a type planer 35 wherein the block and the device for applying pressure thereto shall be combined in a single tool, so that neither of the parts can be separately misplaced or lost; to provide a type wherein the force or strength of the 40 blow may be so limited as to prevent injury or destruction of the face of the type when forms are being planed; to provide a planer block of such a construction that, when moved over the face of the type, it will 45 not injure the latter; to provide a type planer which will reduce the noise usually accompanying the operation of such devices; to provide a type planer which will 50 make impossible the infliction of injury to the hands or fingers of the printer when planning; and, generally, to provide a type planer combining simplicity of construction and operation with low cost and increased 55 facility of operation. With these and other objects in view, which will be apparent from the following detailed description, our in-

vention consists in the new and improved structural features of a type planer, substantially as hereinafter described and illustrated in two practical forms in the accompanying drawings, in which

Fig. 1 is a perspective elevation of a simple form of our improved type planer;

Fig. 2 is a longitudinal section of the same; and

Fig. 3 is a longitudinal section of a modified form employing spring means for returning the mallet to elevated position.

Referring to the drawing, 5 designates a rectangular block preferably of hard wood, 70 the lower working face of which is formed with rounded longitudinal and transverse edges 6 and 7 and rounded corners 8; the purpose of this latter structural feature being to enable the block to be easily moved 75 sidewise or endwise over the face of the form without striking and blunting or chipping the fine edges of the type. In the center of the block 5 is formed a hole or well 9, in which is preferably set a metal cylinder 80 10, the upper end 10^a of which preferably projects slightly above the top surface of the block 5. The cylinder 10 is preferably stepped on a leather or fiber disc 11 which fits the bottom of the well 9. Secured to the 85 top of the block 5 by screws 12 is a cover plate 13 having an upwardly offset central portion 14 provided with a central aperture 15 and a countersunk lower edge 16 which fits over the upwardly projecting end 10^a of 90 the cylinder or lining 10.

The mallet comprises a metal head or plunger 17 loosely fitting the cylinder 10 and fast on the end of a vertical stem 18 which passes through the hole 15 of the 95 cover and terminates at its outer end in a handle 19. On the upper side of the plunger 17 is a washer 20 of rubber, felt or other yieldable material which cushions the impact of the plunger 17 against the under 100 side of the cover portion 14 and deadens the noise.

In the operation of the tool, the block 5 is laid on the type form and, as it is shifted from place to place, the handle is raised and 105 depressed, and owing to the comparatively short vertical stroke of the same, it is impossible to impart excessive blows such as would injure the type. The downward blow is cushioned by the yieldable disc 11, which also 110 greatly reduces the noise of the operation.

In Fig. 3 we show a modification, wherein

the block 5^a is formed with a central well 24, and on either side thereof with smaller wells or chambers 25 in which are seated compression springs 26. The plunger head 5^b 27 is secured to the lower ends of the stem 28, the latter passing through the aperture 29 in the cover plate 30 and terminating in a knob or handle 31. Also secured to the stem 28 and conveniently integral with the 10 plunger 27 are a pair of lateral arms 32 which extend into the spring chambers 25 and rest upon the upper ends of the springs 26. Washers 11' and 20', similar in location and function to the washers 11 and 20 of 15 Fig. 2 are also employed to cushion the blows and deaden the noise. The operation of this form of the planer is similar to that of the form shown in Figs. 1 and 2, except that the mallet, after being forced down- 20 wardly to strike the blow is automatically returned to raised position by the springs 26. So far as we are aware, our present in- 25 vention is the first in the art wherein the planer block and the instrument for trans- 30 mitting the blows thereto are combined in a single tool. As above pointed out this ar- 35 rangement involves a number of practical ad- 30 vantages, including the prevention of the loss or misplacement of the mallet, the limi- 35 tation of the thrust of the latter so as to 40 avoid injury to the type, the avoidance of injury to the hands or fingers of the operator, and the wearing down of the upper sur- 45 face of the block through repeated blows 50 of the mallet. Furthermore since the blow is confined to the center of the block, the force of the blow is uniformly distributed from the middle to each end and the consequent pressure on all of the type covered by the block is uniform.

Manifestly, the structural and operative principles of our invention may find embodiment in other specifically different forms; and hence we do not limit the invention to the exact structures herein shown and described, except to the extent clearly indicated in specific claims.

We claim:

1. A printer's type planer, comprising a 50 block, a mallet, and means for connecting said mallet to said block, said connecting means also serving to limit the length of stroke of said mallet on said block.

2. A printer's type planer, comprising a 55 block, a mallet, and means for connecting said mallet to said block with capacity for a limited up and down movement relatively to the latter.

3. A printer's type planer, comprising a 60 block, a mallet, and means for confining said mallet on said block, said confining means also serving to guide the up and down movements of said mallet on said block.

4. A printer's type planer, comprising a block formed with a central chamber, a 65 mallet having a head slidably mounted in said chamber, a stem extending above said block, and a handle on said stem, and means for confining said mallet head in said chamber with capacity for a limited up and 70 down movement.

5. A printer's type planer, comprising a block formed with a central chamber, a mallet having a head slidably mounted in said chamber, a stem extending above said 75 block, and a handle on said stem, and a cover plate secured to the top of said block, said cover plate being formed with an aperture forming a guide for said mallet stem.

6. A printer's type planer, comprising a 80 block, a mallet, means connecting said mallet to said block with capacity for a limited up and down movement, relatively to the latter, and spring means for urging said mallet to fully raised position.

7. A printer's type planer, comprising a block formed with a central chamber, a mallet having a head slidably mounted in said chamber, a stem extending above said block, and a handle on said stem, means for 90 confining said mallet head in said chamber with capacity for a limited up and down movement, and spring means urging said mallet to fully raised position.

8. A printer's type planer, comprising a 95 block formed with a central chamber, a mallet having a head slidably mounted in said chamber, a stem extending above said block, and a handle on said stem, a cover plate secured to the top of said block and formed with an aperture constituting a 100 guide for said stem, a pair of lateral arms on said stem within said chamber, and a pair of compression springs in said chamber beneath and upholding said arms.

9. A printer's type planer, comprising a block formed with a central chamber, a mallet having a head slidably mounted in said chamber, means for confining said 110 mallet on said block, and a cushioning and sound-deadening washer interposed between the lower face of said head and the bottom of said chamber.

10. A printer's type planer, comprising a block formed with a central chamber, a 115 mallet having a head slidably mounted in said chamber, a cover plate confining said mallet head in said chamber, a cushioning and sound-deadening washer interposed be- 120 tween the lower face of said head and the bottom of said chamber, and a like washer interposed between the upper face of said head and said cover plate.

JOSEPH T. BARTON,
EDWARD J. O'LEARY.
